UNITED STATES PATENT OFFICE.

OWEN FIELDING, OF OLIVE HILL, KENTUCKY.

BRICK MACHINE.

Application filed November 27, 1926. Serial No. 151,084.

This invention relates to brick making machinery, and particularly to a brick press which is capable of operating to produce bricks of different shapes and sizes, and it is 5 an object of this invention to provide novel means whereby the form or operating elements which coat to produce the brick may be expeditiously changed and made effective for operation.

10 It is a further object of this invention to produce a brick pressing machine in which force is applied to two sets of pressing elements, each set consisting of two oppositely actuated pressing elements; and furthermore 15 to provide means by which these pressing elements are moved simultaneously in order that the material being worked may have pressure applied to it from four sides, or from two sides and its two ends.

20 It is a still further object of this invention to produce a machine of the character indicated of compact character occupying comparatively little space and having structural features of simple character, compared with 25 the results attainable.

With the foregoing and other objects in view, the invention consists in the details of construction, and in the arrangement and combination of parts to be hereinafter more 30 fully set forth and claimed.

In describing the invention in detail, reference will be had to the accompanying drawings forming part of this application wherein like characters denote corresponding parts 35 in the several views, and in which—

Figure 1 illustrates a view in side elevation of a press embodying the invention;

Figure 2 illustrates a plan view of a plunger guide;

40 Figure 3 illustrates an end elevation with parts omitted;

Figure 4 illustrates a plan of the bed frame and the mold, showing parts associated with it;

45 Figure 5 illustrates a detail view of the mold and the end pressure applying means;

Figure 6 illustrates a plan view of the upper or top cross head;

Figure 7 illustrates a detail view of the 50 mold and parts associated with it;

Figure 8 illustrates a perspective view of a roller mounting and follower; and

Figure 9 illustrates a perspective view of a presser head.

55 In these drawings 10 and 11 denote the end frames having clearances at their longi-

tudinal centers for the reception of the presser box, the sides 12 and 13 of which are secured therein by fastenings 14 such as screws which extend through flanges or lugs 60 15 of the frame member. Presser heads 16 and 17 operate from below and from above, respectively, between the sides of the presser box or mold. The head 16 is associated with an anti-friction roller 18 mounted there- 65 under, which roller is engaged by a rotatable cam 19. The cam is mounted on a main shaft 20 journaled in appropriate bearings in the frame members and the said shaft projects beyond the sides of the frame members. 70 Gear wheels 21 and 22 are secured on the shaft 20 and these wheels are also provided with wrist pins 23 and 24, respectively, on which blocks or boxings 25 are mounted, for 75 a purpose to be presently explained.

The wheels 21 and 22 are supplied with side cams such as 26 and the cams are each intended to engage a roller 27 of a follower 28 to which a presser head 29 is preferably 80 dovetailed. The presser head may be of any appropriate surface configuration to produce 85 proper contour, either straight or ornamental, to the material to be treated or pressed. It is obvious that presser heads of different thicknesses may be employed, and owing to the dovetailed joint between the presser head and the follower, these presser heads may be changed expeditiously in order 90 that brick or plastic articles of different sizes or shapes may be made by the same machine using only different presser heads.

The sides 12 and 13 of the mold have slots 95 at their ends extending longitudinally, and these slots are clearances for lugs 31 on the follower, and when the follower is applied to the mold, the follower is guided by reason of the arrangement described. The outer end of each follower is recessed as at 32 for the reception of a roller 27 whose trunnions 34 and 35 rotate in bearings such 100 as 36 formed in the follower, and the relation of parts is such that the peripheries of the rollers are exposed at the ends of the mold in positions to be engaged by the side cams of the gear wheels 21 and 22. The lugs 31 of the follower are under pressure of 105 springs 37, which springs are located in seats or recesses in the ends of the sides of the mold, and the springs 37 act to urge the follower outwardly against the action of the cams, but the cams, of course, overcome the 110 pressure of the springs and force the fol-

lower and the presser heads inwardly while they are in engagement with the rollers, but when the cams have passed the rollers and released them, the springs will force the following lower and the presser heads outwardly to free the material and permit its being displaced from the mold free of the end presser blocks.

10 The bottom presser operates between the sides of the mold and serves to lift or displace the pressed material from the mold, and the relation of parts is such that after the top presser head has coated with the lower presser head to compress the material, 15 the upper presser head is carried above the top of the mold to a degree which will afford a clearance for the ejection of the finished product from the mold in order that it may be delivered to a take-off, as will 20 presently appear.

An upper cross head 38 reciprocates between pairs of guides 39 and 40, and it may be of a configuration illustrated in Fig. 6 in order that it will have proper guide engaging surfaces such as 41. The cross head 38 has extensions with wrist pins 42 to which bearing blocks 43 are applied. The bearing blocks 25 and 43 are provided with connecting rods or links 44 arranged in pairs on each side of the machine. The rods or links are secured in or to the bearing blocks 25 and reciprocate through the bearing blocks 43, and the upper ends of the rods or links are threaded for the engagement of nuts 45.

35 Springs 46 are applied to the rods or links between the bearing blocks 43 and the nuts, and the said nuts are adjustable to increase or diminish the pressure of the springs. A rock shaft 47 is mounted transversely of the cross head 38 and it constitutes a trunnion for the upper presser head or plunger 17, it being shown that the structure of the presser head or plunger includes an extension or presser bar 48 which projects through a guide 49 secured to the guide posts 39 and 40. This relation of parts insures stability and effective operation, and results in holding the presser bar 48 of the presser head or plunger centrally of the structure, preventing undue arching or wedging of the brick.

This machine has a conventional type of charger 50 which reciprocates over the bed and the mold and it is operated by links 55 such as 51 that are connected to arms 52 that are oscillatable and moved by means to be presently explained. The presser head 17 is on the extension or plunger 48 as has been described, and the manner of connecting these parts may be changed to suit particular requirements, but, in the present embodiment of the invention, they are secured together by fastenings 53, such as screws or the like.

65 The take-off or device which removes the

product from the machine consists of a conveyer apron 54 operating over an idler or roller 55 journaled transversely of the machine in advance of the guides and over a drum or roller 56 suitably journaled in the side members of the frame or in bearings such as 57 applied to the frame. A shaft 58 of the drum 56 has a sprocket wheel or other driven wheel 59 mounted on it and it is engaged by a flexible element 60 such as a sprocket chain that operates over a sprocket wheel 60^a rotatable on a rock shaft 61 journaled in the end frames. The sprocket wheel 60^a is attached to a gear wheel 62 which is loose on the shaft 61 and the gear wheel 62 is rotated through its engagement with a gear wheel 63. A driving shaft 64, which may have power applied to it by any of the well known means for transmitting power, is journaled in the frame and it has the sprocket wheel 63 secured to it and it meshes with the gear wheels 21 and 22. A pinion 65 meshes with the gear wheel 62 which, as stated, runs loosely on the rock shaft and through this gearing the conveyer 54 is operated. The arms 52 are mounted on the rock shaft and the rock shaft is rocked through an arm 66 secured on the rock shaft and a link 67 pivoted thereto, which link is oscillatably mounted on a wrist pin 68 which is extended from the wrist pin 23. As the gear wheel 21 rotates and the wrist pin 23 is carried around with it, a throw will be imparted to the link 67, which in turn will rock the shaft and operate the charger. 100

It will be apparent from an inspection of the drawing and the description that material will be delivered to the press periodically by the charger and that after the material or pressed brick has been ejected and it will by the charger be delivered to the take-off, and through the gearing and instrumentalities described, the finished product may be delivered to any appropriate carrier, from which it may be removed from the machine.

The material is cut in conventional way from a column of plastic material and placed in front of the charger. The means 115 for delivering it to the location in front of the charger does not form a part of the present invention and is therefore not described in detail. As the charger reciprocates over the bed, the material is placed 120 in the mold or press box. When material is being placed in the press box, the end presser heads have been forced outward, leaving a clearance for the material to descend into the press box. When material is in said 125 position, the end presser heads are forced toward each other imparting a pressure endwise to the material, while at the same time the lower presser head is moving into the box, causing the material to be pressed both 130

vertically and horizontally simultaneously. After the material is pressed, the cams 26 disengage the rollers and allow the presser heads to be forced outwardly by the springs, and these springs are relatively strong in order that this movement of the presser heads outwardly may be practically instantaneous with their release and freeing the brick or finished product to be forced to the top of the press box by the cam 19. The second or succeeding material being delivered by the charger encounters the finished product or brick and pushes it on to the transfer or off bearing conveyer 54, which may deliver it to the end where it may be taken off.

As the description of the operation of the several parts of the machine has been given in connection with the description of the parts and their relation to other parts, a further résumé of the operation is believed to be unnecessary for an understanding of the invention by one skilled in the art.

I claim:

1. In a brick press, frame members having openings at their upper edges, press box sides secured in vertical positions therein, a bottom presser head operating between the sides of the box, means for supporting the presser head near the bottom of the box during the pressing operation, means for forcing the said head upwardly to eject the product, pressing elements slideable in the ends of the press box, cams rotatably mounted in operative relation to the pressing elements for forcing said pressing elements inwardly, and means for moving them outwardly.

2. In a brick machine, a frame having a transversely disposed press box, laterally movable presser heads in said box, cams rotatably mounted in operative relation to the pressing elements for forcing said pressing elements inwardly, means for moving them outwardly, a lower presser head in said box, means for supporting said head at the bottom of the box during the pressing operation and for moving the said presser head vertically for ejecting the product after pressure has been applied thereto, and means for applying pressure from the top of the box.

3. In a brick machine, a frame having a transversely disposed press box, a lower

presser head and an upper presser head in operative relation hereto, presser heads mounted for movement in the ends of the box, anti-friction elements on the last mentioned presser heads and cams rotatably mounted for engaging the anti-friction elements and forcing the presser heads inwardly, means for retracting said presser heads, and means for operating the upper and lower presser heads.

4. In a brick press, a frame having upwardly extending guides, a cross head guided thereby, a press bar oscillatably mounted in the cross head, a guide connected to the said upwardly extending guides in which the bar is slideable, a presser head on the lower end of said bar, and a press box in conjunction with which the presser head operates.

5. In a brick press, a frame having upwardly extending guides, a cross head guided thereby, a press bar oscillatably mounted in the cross head, a guide connected to the said upwardly extending guides in which the bar is slideable, a presser head on the lower end of said bar, a press box in conjunction with which the presser head operates, a bottom presser head adapted to contact with the first mentioned presser head, pressing elements movable in the ends of the box, means for imparting movement to the said pressing elements simultaneously, and means for retracting the said pressing elements.

6. In a brick press, a frame having upwardly extending guides, a cross head guided thereby, a press bar oscillatably mounted in the cross head, a guide connected to the said upwardly extending guides in which the bar is slideable, a presser head on the lower end of said bar, a press box in conjunction with which the presser head operates, a bottom presser head adapted to contact with the first mentioned presser head, pressing elements slideable in the ends of the box, rollers constituting a part of the pressing elements having their peripheries exposed at the ends of the press box, rotatable elements in the sides of the frame having cams for engaging the rollers for forcing the pressing elements inwardly, and means for forcing the pressing elements outwardly when released from the cams.

OWEN FIELDING.
